DISPENSING HOLDER FOR COLLAPSIBLE TUBES

Floyd T. Holloway and Benjamin J. McKinney,
Clovis, N. Mex.

Application October 8, 1948, Serial No. 53,496

3 Claims. (Cl. 222—104)

1

My invention relates to dispensing holders for collapsible tubes, such as are utilized for containing tooth paste, shaving cream, and the like.

With the foregoing in view, it is an object of my invention to provide an improved dispensing holder for collapsible tubes.

A further object is to provide an improved dispensing holder for collapsible tubes which includes a relatively simple structure adapted to be supported on a support, means for mounting a collapsible tube in dispensing relation to the holder, and a combined closure cap and cut-off for the tube contents operatively carried by the holder.

Other objects and advantages reside in the particular structure of the invention, combination and arrangement of the several parts thereof, and will be readily understood by those skilled in the art upon reference to the attached drawings in connection with the following specification, wherein the invention is shown, described and claimed.

In the drawing:

Figure 1 is a front elevation of the holder according to the invention showing the same in use;

Figure 2 is a horizontal sectional view taken substantially on the plane of the line 2—2 of Figure 1;

Figure 3 is a fragmentary vertical sectional view taken substantially on the planes of the lines 3—3 of Figure 1;

Figure 4 is a horizontal sectional view taken substantially on the plane of the line 4—4 of Figure 1;

Figure 5 is a perspective view of a detail of the invention;

Figure 6 is an enlarged perspective view of a further detail of the invention apart from the rest of the structure.

Referring specifically to the drawing, wherein like reference characters have been used throughout the several views to designate like parts, 10 designates generally any suitable base which, in the form illustrated, comprises a plate bent or otherwise formed into L-shaped configuration so as to provide a vertical flange 11 and a horizontally-disposed flange 12. The vertical flange 11 is adapted to be secured by any suitable means, such as the screws 16, to any suitable support, such as the wall 14. One or more edges of the horizontal plate 12 may be formed with restricted notches 15 adapted to receive the handles of toothbrushes 16 therein. The horizontal flange 12 of the base 10 is formed with an internally-

2

threaded opening 17 therethrough which is adapted to threadedly receive the externally-threaded neck 18 of a collapsible tube 19. As is clearly seen in Figures 1 and 3, the horizontal plate or flange 12 is of a thickness greater than the length of the neck 18, whereby the free open end of the neck 18 is disposed upwardly of the under surface of such plate or flange 12. The under surface of the plate or flange 12 is formed with a suitable transverse recess 20 which may be in the form of a dovetail groove which intersects the opening 17. As best seen in Figures 1, 4 and 5, a plunger 21 is provided with a shape complementary to the groove 20 and slideable therein. The plunger 21 includes an inner end 22 of reduced thickness which is adapted to be projected across the opening 17 below the free open end of the neck 18 whereby to seal the opening. As best seen in Figure 5, the front end 22 of plunger 21 is defined by an arcuate shoulder 23 which is substantially complementary to the curvature of the neck 18. Thus, the upper surface of the plunger 21 outwardly of the shoulder 23 is not projectable across the mouth of neck 18 and is protected against contact with the tube contents. Likewise, the upper surface of the reduced inner end 22 of the plunger does not contact the ceiling of the groove or recess 20 whereby none of the tube contents is smeared or otherwise transferred to the ceiling of the groove as the plunger is retracted. Thus, the groove and main body of the plunger are protected against contact with the tube contents. Consequently, free sliding of the plunger is assured as there is little or no chance of the tube contents being smeared between abutting surfaces of plunger 21 and groove 20 to cause sticking of the plunger. The plunger 21 is likewise provided with a downwardly-turned or directed outer end 24 providing a finger grip whereby the plunger may be actuated inwardly and outwardly in the groove 20. To dispense the contents of the tube, we may provide a key 25 which includes a finger grip 27 and a slot 26 adapted to receive the upper end of the collapsible tube 19 therein. Thereafter, the key 25 is rolled downwardly to and beyond the broken line position of Figure 1 to wind the upper end of the tube therearound and dispense the contents thereof in a well known manner.

As is apparent from the foregoing, the plunger 21 not only provides a closure for the opening 17, but also provides a cut-off for the contents of the tube and a seal for the free open end of the same. Thus, when, for instance, tooth paste

is to be dispensed to a toothbrush 16, such brush is placed in the broken line position of Figure 1, and the key 25 is rolled downwardly to dispense any desired amount of the tube contents outwardly of the opening 17. Of course, the plunger 21 has been previously retracted to the broken line position of Figure 1, whereby the inner end 22 is retracted from across the opening 17. When a sufficient quantity of tooth paste has been squeezed out of the tube 19, the plunger 21 is moved to the full line position of Figure 1, at which point the reduced inner end 22 automatically cuts off the supply of tooth paste and seals the free open end of the neck 18. Obviously, the simplicity of the structure renders its operation self-evident in view of the foregoing, but it is obvious that the device could be used for dispensing of shaving cream or other goods contained in collapsible tubes.

Likewise, although we have shown and described what is now thought to be the preferred embodiment of our invention, it is to be understood that the same is susceptible of other forms and expressions. Consequently, we do not limit ourselves to the precise structure shown and described hereinabove except as hereinafter claimed.

We claim:

1. In a dispensing holder for collapsible tubes of the type including an externally-threaded neck formed with a free open end, a base, means for mounting said base on a support, said base being formed with an internally-threaded opening therethrough adapted for threaded engagement with said neck of said tube, said opening being substantially longer than the length of said neck, said base being formed with a recess therein intersecting said opening in the region of said free open end of said neck, a plunger slidable in said recess, said plunger including an inner end of reduced thickness extensible across said opening to close the same, said inner end being defined by an arcuate shoulder, and said inner end of said shoulder comprising means for preventing smearing of the tube contents in said recess.

2. In a dispensing holder for collapsible tubes of the type including an externally-threaded neck formed with a free open end, comprising a flat plate having upper and under surfaces, said plate being adapted to be mounted on a support

so as to project horizontally therefrom, said plate being formed with a vertically-disposed and internally-threaded opening, said neck being adapted to be threaded into said opening from above to dispose said tube above said plate, said plate being of greater thickness than the length of said neck, said under surface of said plate being formed with a dovetail groove extending transversely of said opening and intersecting the same, a plunger complementary to said groove and adapted to slide therein, said plunger including an inner end of reduced thickness adapted to be projected across said opening to close the same, said inner end being defined by an upwardly-directed shoulder, said inner end and said shoulder comprising means preventing the contents of said tube from being smeared along said groove as said plunger is retracted to uncover said opening, and said plunger including a downwardly-directed outer end providing a finger grip.

3. In a dispensing holder for use with collapsible tubes of the type including a neck formed with a free open end, a base adapted to be mounted on a supporting surface, the open end of the neck of the tube extending through one face of said base and terminating at a point spaced from the other face of said base, and a plunger positioned within the space adjacent the other face of said base and slidably supported in said base for movement into and out of bridging relation with the open end of said neck, the bridging part of said plunger being cut away to thereby prevent smearing of the tube contents along said other face of said base as said plunger is moved out of bridging relation with the open end of said neck.

FLOYD T. HOLLOWAY.
BENJAMIN J. MCKINNEY.
